UNITED STATES PATENT OFFICE.

JOHN SQUIRES, OF DETROIT, MICHIGAN, ASSIGNOR TO SIGNAL MOTOR TRUCK COMPANY, OF DETROIT, MICHIGAN, A CORPORATION OF MAINE.

DESIGN FOR A TRUCK-FRAME.

50,045.

Specification for Design.

Patented Dec. 12, 1916.

Application filed March 18, 1916. Serial No. 85,223. Term of patent 7 years.

To all whom it may concern:

Be it known that I, JOHN SQUIRES, a citizen of the United States of America, residing at Detroit, in the county of Wayne and State of Michigan, have invented a certain new, original, and ornamental Design for Truck-Frames, of which the following is a specification, reference being had therein to the accompanying drawings, forming part thereof, in which the figure is a side eleva-

tion of a truck-frame, showing my new design.

I claim:

The ornamental design for a truck frame, substantially as shown.

JOHN SQUIRES.

Witnesses:

JAMES P. BARRY,
ARTHUR D. PULVER.
